UNITED STATES PATENT OFFICE.

CARL EDUARD RÜGGEBERG, OF REMSCHEID, GERMANY.

DEVICE FOR FIRMLY ATTACHING EXCHANGEABLE BLADES TO HOES, MATTOCKS, OR THE LIKE.

Application filed March 9, 1928, Serial No. 260,402, and in Germany January 4, 1927.

This invention relates to a hoe or mattock, or similar implements, having a detachable or exchangeable blade to be clamped fast on its neck, and the novelty consists in that the 5 later extends at its front end into a broad flange with straight smooth front surface and a dovetail-shaped projection on the latter, that is slightly tapered downwardly to engage firmly by wedging action with a correspondingly tapered slot in the blade of the 10 hoe or mattock.

The accompanying drawing illustrates the improved arrangement:

Figs. 1 and 2 are respectively a side view 15 and a front view of the neck of a hoe or mattock with inserted blade,

Fig. 3 is a front view of the detached blade, and

Fig. 4 is a section on the line 4—4 of Fig. 20 2, looking down.

The neck *a* of the hoe or mattock, which at its rear end terminates in a lug *b* for its attachment to a handle extends, according to the invention, at its front end into a broad 25 flange *c* with straight smooth front surface *d*. The latter has a dovetail-shaped lug or projection *f* thereon, that is slightly tapered in downward direction. Corresponding to the taper of said projection, the blade *g* of 30 the hoe or mattock, that is detachably fixed on the neck *a* has tapered slot *h* for engagement with the depressions *e* in the edges *e* of said projection, which slot can be open-ended as shown or closed.

Said blade is firmly driven upon the neck 35 *a* by wedging action when striking the said

neck upside down on a firm base, its back lying then flat upon the straight smooth front surface *d* of flange *c*. When using the hoe or mattock, its blade is continuously 40 driven fast by the blows exerted with the blade, so that it cannot get loose.

It is obvious that the improved mode of attachment can also be applied to similar implements having a detachable blade. 45

What I claim, is:

1. In a hoe or mattock, the combination of a neck, a broad flange with a flat face on the front end of said neck, a projection on the front surface of said flange dovetailed in 50 cross-section toward said face and slightly tapered downwardly, a removable blade and a correspondingly tapered open-ended slot in said blade, the inner walls of said slot being perpendicular to the face of said blade. 55

2. In a tool of the type having a handle and a detachable working element extending transversely thereto, engaging means between said handle and said element, said means comprising a slot in said working element 60 narrowing towards one end, and an end on said handle comprising a broad supporting flange having a lug thereon, said lug being shorter than said slot and correspondingly tapered longitudinally, whereby to wedge 65 against the sides of said slot, and having inwardly-inclined edges whereby to clamp the working element in a direction normal to said wedging action.

In testimony whereof I have hereunto set my hand.

CARL EDUARD RÜGGEBERG.
